UNITED STATES PATENT OFFICE.

THOMAS H. MCQUOWN, OF CAMBRIDGE, MASSACHUSETTS, ASSIGNOR, BY MESNE ASSIGNMENTS, TO ARTHUR ATWATER KENT, OF PHILADELPHIA, PENNSYLVANIA.

SPARKING DEVICE.

950,339.

Specification of Letters Patent. Patented Feb. 22, 1910.

Application filed July 28, 1905. Serial No. 271,583.

To all whom it may concern:

Be it known that I, THOMAS H. MCQUOWN, a citizen of the United States, residing at Cambridge, county of Middlesex, 5 and State of Massachusetts, have invented an Improvement in Sparking Devices, of which the following description, in connection with the accompanying drawing, is a specification, like characters on the drawings 10 representing like parts.

This invention relates to an electric make and break device, and among the objects of the invention are to provide a device of this character in which the contacts are separated the instant that they are brought together, and are therefore in contact a minimum length of time regardless of the speed at which the device is operated, and also to provide a novel arrangement by which the 20 closing and opening of the contacts may be made to make and break any one of a plurality of circuits.

The invention is herein illustrated as embodied in a timer and distributor adapted 25 for use in connection with gas or gasoline engines, but I wish it understood that my invention is not limited to use in connection with a device of this character but may be employed in other machines where it is desirable to make and break an electrical contact. The make and break device comprises 30 two contacts, (which I will designate as the "stationary" and the "movable" contact respectively,) means tending normally to accelerate the movement of the movable contact toward the stationary contact, and a restraining device to restrain or retard the movement of the movable contact until it is about to engage the stationary contact, 35 whereby when the restraining device ceases to operate the movable contact wipes over or by the stationary contact with an accelerated movement, thereby opening the contacts the instant they are closed.

40 The device also comprises a suitable circuit controller or distributor by means of which the contacts are thrown into any one of a number of different circuits.

In the drawings, Figure 1 is a view of my 45 improved device with the cover of the casing removed, said view also showing the electrical connections; Fig. 2 is a section of the

casing on the line $x-x$, Fig. 3; Fig. 3 is a section on the line $y-y$, Fig. 1; Fig. 4 is a section on the line $a-a$, Fig. 3; Fig. 5 is a 55 section on the line $b-b$, Fig. 3; Fig. 6 is a detail of the brush of the circuit controller or distributor.

I will first describe the make and break device. 60

3 and 4 designate the two contacts which are closed and opened again by a relative movement between them. The contact 3 is relatively stationary, and for convenience I will hereinafter refer to it as the "stationary" contact. It is preferably mounted upon a resilient arm 5 which is supported in any suitable way, as for instance by being secured to one wall of the casing 6 within which the movable parts of the device are 70 located. The contact 4, which I have termed for convenience the "movable" contact, is adapted to move toward and from the stationary contact and in its movement to engage said stationary contact. In the present embodiment of my invention said contact 4 is carried by a plate or disk 7 rotatably mounted upon a stud 8 sustained by the casing. The plate 7 is rotated by means which tends constantly to accelerate its movement, 75 and it is restrained or retarded in its movement until just before the contact 4 is about to engage the stationary contact 3 when said restraining means becomes inoperative and the plate rotates forward with a quick accelerated movement, thereby causing the contact 4 to wipe past the stationary contact 3. 85

In the embodiment of the invention herein illustrated the plate or disk 7 is driven from a gear wheel or pinion 9 loosely mounted on the stud 8, the driving connection between the pinion and disk being a spring 10 which is connected at one end to a pin 11 projecting from the disk 7 and at the other end to a pin 12 carried by the 90 pinion 9, said pin 12 extending through a slot or opening 13 in the plate 7. With this construction the plate and pin may move independently of each other about the stud 8, and if just before the contact 4 engages the contact 3, or in other words if at the time said contact 4 occupies the dotted line position Fig. 2, the movement of the plate 95 is restrained the forward movement of the 100

pinion will wind the spring 10 up so that when the plate 7 is released the spring will act to impel said plate forward with a rapid movement, thereby closing and instantly opening the contacts.

The pinion 9 may be driven in any suitable way. As herein shown it is driven from a pinion 13 mounted on a spindle or distributor shaft 14 which forms in effect a continuation or extension of a shaft 15. This shaft 15 may be any suitable shaft on or forming part of the machine with which the device is to be used, as for instance the crank-shaft of a gasoline engine. Said shaft has therefore a regular forward movement and through the pinion 13 it gives such regular movement to the driven pinion 9. I prefer to insulate the spindle 14 from the shaft 15, although this is not essential to my invention. As herein shown however the end of the shaft 15 has fast thereon a sleeve 16 provided with a projection 17, and said projection 17 has a sleeve or covering 18 of insulating material. Fast on the insulated extension or projection 17 is the hub 19 of the spindle 14. This hub 19 is shown as rotatably mounted in a bearing sleeve 20 carried by a hub or boss 21 which forms the bearing for the extension of the shaft 15. The gear 13 may be either fast to the spindle 14 or it may be driven from the spindle by a pawl and ratchet connection. I prefer the latter construction because this permits a backward motion of the shaft 15 without moving the parts of the sparking device. The pawl and ratchet connection is formed by a spring pressed pawl 22 pivotally mounted on an extension 23 of the hub of the gear 13 and adapted 40 to engage a ratchet tooth 24 formed in a collar 25 fast on the spindle 14.

The restraining device or the means for restraining the accelerated movement of the plate 7 is herein shown as a tooth or teeth 26 formed on or carried by the plate 7 and coöperating with a tooth or teeth 27 rotating with the spindle 14. For convenience I propose to make the teeth 27 rigid with the hub of the pinion 13 although this construction is not essential. The teeth 26 and 27 are so arranged and shaped that the tooth 27 is engaged by the tooth 26 and restrains or retarded the movement of the plate 7 relative to the pinion 9 as the contact 4 is approaching the contact 3, and during this interval therefore the pinion 9 moves ahead of the plate 7 and winds up the spring 10. When the teeth 26 and 27 come into the dotted line position Fig. 2 the contact 4 is just about to engage the contact 3, and said teeth are so shaped that at this instant the tooth 26 slips by the tooth 27 thus allowing the spring 10 to come into action to give the

plate an accelerated movement and cause the contact 4 to wipe past the contact 3.

66

It is entirely within my invention to use only one movable contact 4, in which case only one tooth 26 and one tooth 27 would be necessary. Where, however, my invention is to be used for making and breaking in succession a plurality of circuits I prefer to use a plurality of contacts 4, as many contacts as there are circuits.

The present embodiment of my invention is adapted to make and break five different circuits, and, therefore, I have illustrated five contacts 4 which are carried by the plate 7, and are adapted one after the other to engage the stationary contact 3. Where five movable contacts 4 are used I propose to employ five restraining teeth 26 and five teeth 27. The number of teeth 26 and 27 however depends upon the particular machine with which my invention is to be used. Where there are a plurality of teeth 26 and 27, as there are in this embodiment of my invention, it will be evident that when one tooth 26 is in engagement with the corresponding tooth 27, as shown in Fig. 2, the movement of the plate 7 will be retarded relative to that of the pinion 9 until said teeth 26 and 27 have reached the dotted line position, Fig. 2, at which time one of the movable contacts 4 is about to engage the stationary contact 3. During this time when the movement of the plate 7 has been retarded the spring 10 has been wound up by the forward movement of the pinion and as the tooth 26 slips by the corresponding tooth 27 the spring gives the plate and movable contact 4 an accelerated forward movement, causing the contact 4 to wipe over the stationary contact 3. Immediately that the contact 4 has separated from the stationary contact 3 this accelerated movement is arrested by the next tooth 26 coming into engagement with the corresponding tooth 27, and the above described operations are repeated. It will thus be seen that the plate 7 carrying the movable contact or contacts is alternately restrained in its movement and then accelerated, the acceleration taking place just when the contacts are about to engage each other. This action takes place regardless of the speed at which the shaft 15 or the pinion 9 is rotated, and therefore even though said parts are moving very slowly yet it will be impossible for the contacts 3 and 4 to remain in contact more than the minimum length of time. I regard this as an important feature of my invention, because by means of it the life of the battery or other source of electricity may be greatly increased.

80

As above stated the invention is herein illustrated as embodied in a timer and dis-

90

10

11

12

tributer for gas and gasolene engines, which distributor is used in connection with an induction coil in a well known way.

In Fig. 1, 30 designates the primary windings of a coil, and 31 the secondary windings. This primary winding is connected to the stationary and movable contacts 3 and 4, the connection with the movable contact being made through wire 33 which 10 connects to the casing 6, said casing being electrically connected with the movable contact 4, and the connection with the stationary contact being made through a wire 34 which leads to a binding post 35 carried 15 by but insulated from the casing, said binding post being connected to the stationary contact 3.

36 designates a battery or other generator in the circuit of the primary coil 30. The 20 circuit 37 of the secondary coil leads to the distributor, presently to be described, which distributor connects said circuit with the various circuits 38, each of which includes a sparking plug shown diagrammatically 25 at 39. In practice each of the circuits 38 will be connected to the frame of the engine which is shown diagrammatically in Fig. 1 at 40, said engine-frame being connected with the circuit 37. The distributor is arranged 30 to connect the various circuits 38 successively with the circuit 37. Said distributor comprises a ring 41 which is sustained by the casing 6 but insulated therefrom by an insulating block 42, a plurality 35 of contact-pieces 43 which are also carried by the insulating block 42 and are insulated from each other, and a brush or wiper 44 which is in constant engagement with the ring 41 and is adapted to move 40 over and engage successively the contact-pieces 43. The ring 41 is electrically connected with the circuit 37, and the contact-pieces 43 are connected with the various circuits 38.

45 45 designates a binding post insulated from the casing 6 and connected to the ring 41, said binding post being connected to one of the wires of the circuit 37. Each contact-piece 43 is connected to a binding post 50 46 which extends through the casing and is insulated therefrom, said binding post 46 being connected to the wires of the various circuits 38.

The brush 44 comprises a head or block 55 47 of insulating material which carries a metallic facing that contacts with the ring 41 and the pieces 43. Said head or block is herein shown as being pivotally mounted upon an arm 48 which in turn is pivoted 60 to a collar 49 fast with the spindle 14. Said brush is normally held against the ring 41 and the contact-pieces 43 by means of a suitable spring 50 which tends normally to

throw said arm outwardly. The contact-pieces 43 are so situated and the speed of 65 rotation of the brush is such relative to the speed of rotation of plate 7 that the brush engages one contact-piece at the time when the corresponding movable contact 4 engages the stationary contact 3. The rotation of the plate 7 and contacts 4 operates to make and break the circuit of the primary winding, and obviously this results in the making and breaking of the circuit of the secondary winding. The latter circuit 70 is completed through any one of the circuits 38 according to the position of the brush 44, and as the brush advances from one contact 43 to another and the successive contacts 4 engage the stationary contact 3, the various circuits 38 will be made and broken successively, as will be obvious.

I prefer to use as many movable contacts 4 as there are circuits 38, yet this is not essential to my invention, for it will be obvious 85 that so long as the circuit of the primary winding is made and broken at the time that the circuit of the secondary winding is completed through any one of the circuits 38, the sparking plug in said latter circuit will 90 be operated, and by proportioning the gearing between the spindle 14 and the pinion 9, the make and break device may be made with one or any other number of contacts 4.

The entire casing 6 may be swung about 95 the sleeve 19 as an axis, and is held in any adjusted position by means of an arm 51 rigid with the casing and adapted to be adjustably secured to a bracket 52. By thus turning the casing slightly with reference 100 to the shaft 15, the point in the cycle of operations of the gas engine at which the sparking plug is operated may be adjusted.

The current generated in the secondary 105 31 of the sparking coil is usually one having comparatively high tension.

I have found that by insulating the distributor and sparking device from the shaft 15 by the sleeve of insulating material 18, as 110 shown in Fig. 3, it is possible to make the operative parts of the distributor and sparking device of less size than where such insulation is not employed.

The casing which incloses the operative 115 parts of my device has a novel construction which has some advantages. Said casing comprises a back 53 on which all the operative parts are supported except the block 42 of insulating material and the ring and segments carried thereby, a body or side portion 54 and a front plate or cap 55. The back is provided with the flanges 56 into which the side portion 54 sets, and the cap is also provided with flanges 57 which set over the side portion. The cap is secured in place by 120 a retainer 58 which screws over the end of 125

the stud 8, see Fig. 3, said screw and stud operating to hold the three parts of the casing together. The entire casing is steadied by means of the projecting end 59 of the 5 spindle 14 which enters a suitable socket 60 in the cap. By means of this construction the cap 55 can be readily removed simply by removing the retainer 58 thus opening the casing for inspection, and when the cap 55 10 has been removed the sides 54 carrying the rings and segments can be removed thus giving access to all the other operative parts of the device.

Various changes in the construction of the 15 parts of the device may be made without departing from the invention.

Having described my invention what I claim as new and desire to secure by Letters Patent is:—

- 20 1. In a device of the class described, a stationary contact, a rotary member carrying a movable contact which is adapted to engage the stationary contact as said member rotates, means tending constantly to rotate said member forward with an accelerated motion, and a rotary restraining device to restrain the movement of said member until the movable contact is about to engage the stationary contact, said restraining device releasing said member just prior to the time when the movable contact engages the stationary contact whereby the movable contact is accelerated in its movement as it engages the stationary contact.
- 25 2. In a device of the class described, a stationary contact, a member carrying a movable contact which is adapted to engage the stationary contact as said member rotates, a rotating driver imparting a continuous rotary movement to said member, a yielding connection between the driver and said member, and means to retard the forward movement of said member until the movable contact is about to engage the stationary contact, said means releasing said member just prior to the time when the movable contact engages the stationary contact.
- 30 3. In a device of the class described, a stationary yieldable contact, a member carrying a movable contact adapted to engage the stationary contact, a rotary driver imparting to said member a continuous movement of rotation, a spring connecting the driver and member, means to retard the rotary movement of the member and thereby store up energy in said spring until said movable member is about to engage the fixed contact.
- 35 4. In a device of the class described, a stationary contact, a rotary member carrying a movable contact, a pinion for continuously rotating said member, a spring connection between the pinion and the member and

rotary means to intermittently retard the movement of said member and to then release said member to allow it to move at an accelerated speed, said contacts being momentarily closed during the accelerated movement of said member.

5. In a device of the class described, a stationary contact, a member carrying a movable contact, a pinion for continuously rotating said member, a spring connection between the pinion and the member, and means to retard the movement of the member until the movable contact is about to engage the fixed contact and to then release said member to cause said contacts to momentarily engage.

6. In a device of the class described, a stationary contact, a plurality of movable contacts adapted to engage the stationary contact successively, means tending to move said movable contacts toward the stationary contact with an accelerated motion, and means to retard the movement of each movable contact as it approaches the stationary contact and until it is about to engage said stationary contact.

7. In a device of the class described, a stationary contact, a plurality of movable contacts adapted to engage the stationary contact at different times, a rotating driver for giving the movable contacts a continuous movement, a yielding connection between the driver and said contacts, and means to retard the movement of each contact relative to the driver while it is approaching the stationary contact and until it is about to engage said contact.

8. In a device of the class described, a stationary contact, a member carrying a plurality of movable contacts, a pinion for continuously rotating said member, and a spring connection between the pinion and member, and a constantly rotating member to intermittently retard the rotary movement of said first mentioned member.

9. In a device of the class described, a stationary contact, a member carrying a plurality of movable contacts, a pinion for continuously rotating said member, a spring connection between the pinion and member, and means to retard the movement of the member during the time that each movable contact is approaching the stationary contact and until said movable contact is about to engage the stationary contact.

10. In a device of the class described a stationary contact, a member carrying a movable contact, means for continuously rotating said member, a yielding connection between said member and said means, and a rotary retarding device for intermittently varying without stopping the movement of said member.

11. In a device of the class described a distributor shaft, a make and break device driven directly from said shaft, and a rotating device mounted on said distributor shaft and coöperating with said make and break device to intermittently retard the speed of said make and break device before the closure of the circuit therethrough, and to release the same immediately prior to the said closure of said circuit, and means to impart

an accelerated movement to said make and break device when released, to momentarily close and break a circuit.

In testimony whereof I have signed my name to this specification in the presence of 1° two subscribing witnesses.

THOMAS H. McQUOWN.
